UNITED STATES PATENT OFFICE.

WILLIAM F. CONRAN, OF BROOKLYN, NEW YORK.

STAND-PIPE SYSTEM.

1,253,005.

Specification of Letters Patent. Patented Jan. 8, 1918.

Application filed March 26, 1917. Serial No. 157,558.

To all whom it may concern:

Be it known that I, WILLIAM F. CONRAN, a citizen of the United States of America, residing in the borough of Brooklyn of the city of New York, in the county of Kings and State of New York, have invented a certain new and useful Improvement in Stand-Pipe Systems, of which the following is a specification.

10 My invention relates to fire extinguishing systems employing a main water supply line or pipe having a number of outlets or branches at various points controlled by hydraulically operated valves which in turn 15 are controlled from distant points or from a common operating station; and my invention relates more particularly to a system of movable stand-pipes for buildings such as described in Letters Patent of the 20 United States No. 816,152, granted to me March 27th, 1906, and embodies new features and details in construction as herein-after more fully set forth.

In the accompanying drawings which 25 illustrate my invention as applied to a movable stand-pipe, Figure 1 is a diagrammatic view representing the front wall of a building and the stand-pipe with its water supply connections; Fig. 2, an enlarged vertical sectional view of the hydraulic-lift; Fig. 3, a sectional view of the base or rest for the stand-pipe; Fig. 4, a vertical sectional view of the control-box or fitting; Fig. 5, a central cross section of half of the control-box 35 fitting showing the covering plate for the hand-hole; Fig. 6, a similar view of the other half of the control-box fitting illustrating the arrangement of control-valves; Fig. 7, a central vertical section through the 40 nozzle-valve and fitting; Fig. 7^a, an enlarged vertical section of the expansion joint shown in Fig. 7; Fig. 8, a horizontal section on the line α — α of Fig. 7; Figs. 9 and 10 are horizontal and vertical sectional views, 45 respectively, illustrating a modified retainer for the control-pipes; Figs. 11 and 12 are plan and partial sectional views of the stand-pipe bearings at each floor; Fig. 13 is a diagrammatic view of the controlling valve for 50 the hydraulic-lift, and Fig. 14, a diagrammatic view of the controlling valve for the piston of the nozzle-valve.

Referring to Fig. 1 of the drawings, 1 represents the front wall of a building; 2, 55 the floors; 3, the cellar floor; 4, the street level, and 5, the entrance to the operating

chamber where the valve controls are located. The stand-pipe 6 extends from the cellar to the roof of the building through guides or bearings 7 secured to the floors or front wall, or both. At each floor and cellar, excepting the ground floor, are shown nozzles 8 mounted on nozzle-valves 9, which in turn are mounted on Y-fittings 10 of special form. Each of these fittings also has mounted thereon a hand-valve 11 to which is attached the ordinary hose line 12. In the section of the stand-pipe passing through the operating chamber is inserted the control-box or fitting 13 upon which a series of hand-valves 14 are mounted for controlling the flow of water through the control-pipes 15 extending to each nozzle-valve 9. Mounted on the stand-pipe above the control-fitting is a pointer 8^a whose position as to height and 75 direction corresponds to the position of the nozzles. These control-pipes are carried within the stand-pipe and project through the control-fitting for connection to valves 14 and through the Y-fittings 10 for connection to the nozzle-valves. The stand-pipe is erected on a base 16 which carries a downward extension and a piston working in cylinder 17 of the hydraulic-lift. The water supply connections for the stand-pipe 80 may be arranged for four sources of supply, as follows: first, the Siamese coupling and pipe 18 for fire-engine service; second, pipe-line 19 for a water-tank service; third, pipe-line 20 for connection to a pump in the building, and fourth, pipe-line 21 for connection to the regular street water main or a high-pressure service. These supply lines connect with pipe 22 which enters the hydraulic-lift 85 cylinder at the bottom, and in each of these lines is placed a check-valve 23 which permits flow of water only in the direction leading to the stand-pipe. From pipe 22 extends a small supply pipe 24 which is connected to one port of a 4-way valve 25 in the operating chamber, and from two other ports of this valve extend pipes 26 and 27 which lead, respectively, to the bottom and top of cylinder 17 for supplying pressure under and above the piston in said cylinder for raising and lowering the stand-pipe. The fourth port of valve 25 has attached to it a drain pipe 28 which may lead to any suitable point for discharge. The stand-pipe may be rotated in either direction, and for this purpose I provide a lever or large spanner wrench 29 engaging pin-

holes in the flange of the control-fitting. In practice the stand-pipe will generally be located as shown near the wall of the building and in such case the nozzles need swing only through an arc of 180°. The arrangement of supply pipes leading to pipe 22 as shown is only diagrammatic, and it will be understood that in practice they will be located in the most convenient manner 5 and so as not to interfere with the operation of or obstruct the stand-pipe or nozzle in the cellar. The same remarks apply to control-pipes 24, 26 and 27, and these will usually be placed against the wall of the 10 operating chamber. The pipe leading from the Siamese coupling 18 is provided with a drain valve 30 and supply line 19 is preferably provided with a gate-valve 31. It will be understood that the positions of the nozzles, the nozzle-valves and fittings, relative 15 to the floors or ceilings, as shown, are not the positions they will be in in actual practice; the positions shown being only for convenience of illustration. In practice the 20 nozzles will be located near the ceilings when the stand-pipe is in its extreme elevated position, and the extent of vertical movement will be governed by the height from floor to ceiling of the lowest ceiling of the 25 building, and the downward movement will be limited by the stop-base 16 striking the top of cylinder 17. This prevents the piston of the hydraulic-lift striking the bottom of the cylinder. When no water is under 30 the piston, the stop 16 will rest on the top of cylinder 17 and all of the nozzles and fittings will be in their lowermost positions. When the pipe is not in operation, the cylinder may be filled with water under the 35 piston to maintain the stand-pipe in its elevated position. The water for this purpose will be supplied from the house tank through control-valve 25 and pipe 26. If preferred a mechanical stop (not shown) 40 may be provided in the operating chamber for locking the pipe in the elevated position after being raised by the lift, and then valve 25 may be turned to open the drain port and the water drawn out of the cylinder by a hand pump. 45

Referring to Figs. 2 and 3 of the drawings, it will be noted that cylinder 17 is of triple thickness, the inner shell or cylinder being of brass or other non-corrosive metal 50 and between the inner and outer cylinders is a lining of any suitable material, such for instance as cement. The outer cylinder is screw-threaded at both ends, and the lower end is screwed into a flange on the base plate 55 32 and the upper end screws into a collar 33. The base plate has a central hole and flange 34 into which is screwed a nipple 35 and to which supply pipe 22 is connected. Within cylinder 17 is a pipe 36 also screwed into flange 34 and extending the height of the 60

cylinder. The stand-pipe 6 is screwed into the reduced flange of base 16 and screwed into a second thread is a pipe 37 of larger diameter than pipe 36. This pipe 37 extends downward as a continuation of the stand-pipe and surrounds the pipe 36. The lower end of pipe 37 carries piston 38. This piston slides on pipe 36 and in contact with the inner shell of cylinder 17. The piston 38, as shown, is provided with a soft metal 70 inner sleeve 39, and a suitable packing and packing ring 40 for making a tight sliding fit on pipe 36; and for a watertight sliding fit with cylinder 17, the piston is provided with upper and lower packings and packing rings 41. At the top of the cylinder, pipe 37 slides in a similar soft metal sleeve 42 and packing and packing ring 43 within collar 33. This collar is provided with a flange 44 upon which the flange 45 of the 75 base 16 rests. Supply pipe 26 enters the bottom of cylinder 17 through base 32 and supply pipe 27 enters the top of the cylinder through collar 33. The entire structure is supported upon a concrete foundation 80. From the foregoing description of the parts comprising the hydraulic-lift it will be observed that the main water supply for the stand-pipe flows directly from the supply pipe 22 and 36 into the enlarged downward 85 extension 37 of the stand-pipe, and that the telescoping connection thus formed and combined with the lift permits free rotary and vertical movement of the stand-pipe, and without being hampered by the water 90 supply connections. This arrangement also permits rotary movement of the stand-pipe to any desired extent according to its location, or if located in the center of a building, the pipe may be given a continuous rotary 95 movement and at the same time an intermittent or continuous vertical movement and thereby reach all parts of a floor within the range of the water pressure. 100

In Figs. 4, 5 and 6 the control-fitting 13 is shown in detail. This fitting may be of any suitable shape, but as shown, I prefer to have the body portion cylindrical in form and tapering toward the ends, and provided with stepped flanges 47 of large diameter. 110 At the thicker part of these flanges I provide bolt-holes 48 which register with bolt-holes in the usual pipe flange shown in dotted lines. The part of flange 47 which projects beyond the pipe flange has a series of pin-holes 49 with which the pins on spanner wrench 29 engage to rotate the stand-pipe. The body part of the fitting has a hand-hole 50 which is covered by plate 51 secured by bolts 52. In casting the fitting it is provided with two semi-circular rows of bosses 53 on the side opposite the hand-hole. These bosses are set at an angle and extend through the wall of the fitting and are oval-shaped in cross section at the exterior end. They 115 120 125 130

have holes 54 (Fig. 6) drilled through to receive the control-pipes 15, the holes being of larger diameter than the pipes to afford space for packing material and packing rings 55 and 56; the former being screwed into the boss from the inside, and the latter having an oval flange and forced against the packing material by screws 57. As shown the control-pipes 15 (only one being shown in Fig. 4) pass downward through the upper bosses 53 and are connected to control-valves 14, it being understood that a control-pipe 15 and valve 14 are provided for each nozzle-valve to be controlled, and that each such pipe and valve is independent of the others. To the inlet side of each valve is attached a short section of pipe 15^a which passes through similar rings 55 and 56 and packing material in the lower boss 53 and to this pipe is attached a strainer 58. As shown in Fig. 4, the control-pipe and valve is for controlling a nozzle-valve located above fitting 13; for a nozzle-valve located below the fitting 13, the direction of pipes 15 and 15^a will be reversed, that is, pipe 15 will project downward through lower boss 53 and pipe 15^a will project upward through upper boss 53. Each control-valve 14 is provided with a drain port 59 to drain the control-pipes or relieve the pressure on the piston of its respective nozzle-valve 9.

Details of construction of the nozzle-valve 9, Y-fitting 10, and the control-pipe supports are shown in Figs. 7 and 8. In my Patent No. 816,152, the valve and fitting are combined in one structure, but that construction is not suitable for the arrangement having the control-pipes located within the stand-pipe, and I also found that it was important to provide a nozzle-valve which would not obstruct the flow of water to the nozzle. To accomplish the latter object I designed the valve so that when opened the seat would present no obstruction to the flow and the valve disk would be withdrawn entirely from the path of the water. In carrying out this construction I make the waterway 60 of the valve in straight cylindrical form, screw-threaded at one end to screw into the Y-fitting 10 and the other end having a flange 61. The valve seat 63, valve disk 65 and its stem are set at an angle of 45° to the waterway and these parts are housed in a cylindrical body 62 and 64 forming a Y with waterway 60. This body 62 and 64 is larger in diameter than waterway 60 and part 62 forms an annular enlargement at part 60 in which the valve seat 63 is removably secured; the depth of the enlargement being such that the valve seat does not project into the path of the water and actually presents an opening larger in diameter than the waterway 60. The inside diameter of cylinder 64 is slightly larger than the diameter of valve

disk 65, and the cylinder terminates in a flange 66. Mounted on cylinder 64 is the piston cylinder 67 having a flange 68, the two flanges 66 and 68 being bolted together with a packing material between them. Cylinder 67 is closed at the inner end by partition 69 having a hole for the valve stem 70. On the valve side of the partition 69 is an annular extension 71 which forms stuffing-box to receive a packing material for the valve stem, and 72 is the packing ring. In the piston cylinder is a piston 73 secured to the end of valve stem 70, and between the piston and the closing cap 74 is a coiled spring 75. One purpose of this spring is to hold valve 65 to its seat when no water is in the stand-pipe and insure its being in the closed position when water reaches the valve. An air hole 76 is provided near the cap of cylinder 67 to prevent air compression in the cylinder and insure the piston moving upward its full extent. The upward movement of piston 73 is limited by stop 74^a on cap 74 against which the end of valve stem 70 strikes. At the lower end of cylinder 67 close to the flange 68 is a screw-threaded hole into which a short piece of pipe 77 is screwed and this pipe is attached to control-pipe 15 by a union 78. In assembling the nozzle-valve, the valve-stem with the valve-disk attached thereto is passed through the stuffing box on partition 69, and the piston 73 is then attached to the stem; the packing material and ring 72 are then placed in position; packing is then placed on the flange 66, and valve-disk 65 is inserted in cylinder 64; flanges 66 and 68 are then bolted together, and finally spring 75 and cap 74 are placed in position. The area of piston 73 is slightly greater than the area of valve-disk 65 so that when water is admitted to cylinder 67 through control-pipe 15, the pressure thereon will exceed the water pressure on disk 65 plus the pressure of spring 75 and open the valve. When the pressure on the underside of piston 73 is relieved by shutting off the water supply at its respective control-valve 14, and opening the drain port thereof, spring 75 will start the valve-disk toward its closed position and the spring pressure plus the water pressure on the back of the valve-disk will finally close the valve and hold it closed until pressure is again admitted to cylinder 67 through pipe 15.

In the patent above referred to, the nozzle is mounted directly upon the nozzle-valve, but in the present arrangement I employ a flanged off-set fitting 79 upon which the nozzle is screwed and by means of which the nozzle is held at an angle. These fittings in practice will be made with off-sets having varying angles to meet varying conditions. The nozzle 8 may be of any approved form, but I provide it with an ex-

terior screw-thread 80 to take standard hose couplings. The object of this is to permit quick attachment of an extra hose line to the stand-pipe without the necessity of first 5 removing the nozzle.

The Y-fitting 10 for the nozzle-valve has a semi-cylindrical or U-shaped central section (see Fig. 8) presenting a flat side which is covered by a plate 81, secured by 10 bolts, and the joint being leaded or packed. The diameter of the central section is greater than the stand-pipe, and tapers at both ends. The ends of the fitting are screw-threaded to receive the screw-threaded 15 ends of pipes 6. The Y-branch 82 projects from the U-shaped body portion of the fitting in a direction parallel with the flat side or plate 81. This plate has a centrally located screw-threaded hole into which a nipple 83 is screwed and upon which the hand-valve 11 is mounted. Thus it will be seen that the hand-valve and nozzle-valve are set at right angles so that in the normal position of the stand-pipe as shown in Fig. 1, 20 the hand-valve and hose will be readily accessible. One control-pipe 15 is led out of fitting 10 at each floor for connection to a nozzle-valve, and as shown in Fig. 7, the fitting for this purpose has a boss at the 25 upper angle of the Y-branch 82 which is bored and packed in the manner described in connection with the fitting of Fig. 4. As hereinbefore stated, the control-pipe for a nozzle-valve in a cellar, or one located below 30 the control-fitting 13, will extend downward and the connections at valve 14 will be the reverse of the connections shown in Fig. 4. For leading pipe 15 out through fitting 10 in the cellar the pipe may have an upward 35 bend and pass up through the stuffing-box for connection to the piston chamber 67. I prefer, however, to provide a boss 10^a through which pipe 15 (shown in dotted lines) will pass; the boss in such case being 40 bored and packed as before explained, and pipe 15 outside of the fitting being provided with a pet-ccck to drain the pipe and cylinder 67 when necessary.

At the upper end of fitting 10 and above 45 the entrance of the Y-branch are two rows of lugs 84 between which are held two U-shaped perforated plates 85, each having a large perforation (see Fig. 8) equal to or larger than the inside diameter of the 50 stand-pipe, and a circular series of small perforations 86. Seated between plates 85 and projecting through perforations 86 are a series of expansion-joints 87 for the control-pipes 15. As shown, these joints are 55 preferably in the form of cylindrical boxes having annular extensions of smaller diameter which fit into perforations 86 of plates 85; the upper extension forming a stuffing-box 90 for the control-pipe section entering 60 from above the joint, and the lower exten-

sion forming one member of a union for attaching the control-pipe section entering the joint from below. The union end of the expansion-joint includes a nipple 88 having its inner end ground conical or 70 spherical to seat against the correspondingly ground end of the box extension, and this nipple has a flange which is engaged by cap 89 and whereby the nipple is held to its seat. The upper ends of the control-pipe sections 75 are screwed into the nipples and thus each section of control-pipe is supported or suspended by the union ends of the expansion-joints. By this means each section of control-pipe is free to contract or expand 80 lengthwise without straining joints or bowing the pipes, and at the same time the expansion-joints and retaining plates 85 support the control-pipes and hold them in position against the interior of the stand-pipe 85 and prevent lateral displacement.

In erecting the stand-pipe upon the hydraulic-lift, pipe 6 with its fittings 13 and 10 may be erected to the full height and then the control-pipes 15, expansion-joints 90 87 and supports 85 may be placed in position, or pipe 6 with its fittings, control-pipes, expansion-joints and supports may be erected together by floors or sections. In either case covering plates 51 and 81 are removed from 95 fittings 13 and 10 to give access to the control-pipes and parts while placing them in position and making connections. The floor bearings are placed in position as the work proceeds, but are not secured until the entire pipe is erected, the Y-fittings alined, and the pipe plumbed. In case repairs or replacements of control-pipes or their connections are necessary, this may readily be done 100 by removing plates 51 and 81 when the joints may be disconnected and the control-pipes removed and replaced. To test the control-pipes and connections, as well as the operation of the nozzle-valves, a water supply pipe may be attached to the drain- 105 port of each valve 14, successively, and the valve adjusted to open communication from port 59 to pipe 15 (see Figs. 4 and 14). The water thus supplied for testing may 110 first be admitted under low pressure to test 115 the movement of the nozzle-valve, and then the pressure increased to test the piping and joints.

In Figs. 9 and 10, I have shown another 120 form of holder for the control-pipes and which form may be employed either with or without the expansion-joints of Fig. 7. In this form I provide a metal ring 91 having a flange 92 which rests on the end of the pipe section entering a fitting 10, the ring 125 91 fitting closely within the pipe. Secured to ring 91 is looped band 93, into the loops of which control-pipes 15 are placed. These loops are intended to hold 130 the pipes in position but allow them to slip

lengthwise, and with this form of support an ordinary screw coupling will be employed to join the pipe sections. In this form, which is suitable for stand-pipes in buildings of ordinary height, the stuffing-box at boss 53 of control-fitting 13 will allow sufficient lengthwise movement of the control-pipes due to expansion or contraction, but in tall buildings where the control-pipes would be much longer, I prefer to arrange them in sections and provide the expansion joints.

In Figs. 11 and 12 are shown in detail one form of floor plate or bearing that may be employed. In these views, 6 is the stand-pipe and 94 is a metal ring having a race for balls 95. This ring is secured by bolts 96 to a floor plate made in two halves 97 and 98. The ball race is covered by plates 99 and 100, and these plates are secured to ring 94 by screws 101. The bearing will be secured to the floor by bolts 102, and in addition it may be secured to an angle plate 103 which is secured to plates 97 and 98 by bolts 104, and which plate 103 is designed to be secured to the wall of the building. The ball bearing is intended mainly to reduce friction in rotating the pipe.

In operating the stand-pipe after water supply is established from either one or more of the four sources of supply, the first step is to open control-valve 25 by moving the handle to position "U", see Fig. 13; this will admit water under piston 38 in the hydraulic-lift and raise the stand-pipe to, or maintain it in, its elevated position. To adjust the height of the nozzles from the ceilings or floors, as may be necessary, valve 25 is moved to position "S" after moving the pipe up or down, closing all ports of the valve and holding the pipe stationary. To move the pipe up or down, the handle of valve 25 is moved either to position "U" or "D" and when the desired height for the nozzle is reached, the handle is again moved to position "S" to bring the pipe to a stop. The height of the nozzles from the ceilings or floors and the direction they are pointing in are indicated by pointer 8^a. The direction of the nozzles is adjusted by rotating the stand-pipe by means of lever 29; the piston 38 acting as a floating pivot for the pipe. The stand-pipe will begin to fill with water as soon as the supply lines are opened, and water may be discharged from any one or all nozzles by opening control-valves 14. When a control-valve 14 is opened by moving the handle to a vertical position, either up or down, water flows through strainer 58, pipe 15, valve 14, and pipe 15 to piston cylinder 67. The water pressure on the underside of the piston overbalances the pressure on valve disk 65 and the pressure of spring 75, and causes the piston to move upward and open the nozzle-valve. To hold

piston 73 and valve-disk 65 in the open position, the handle of control-valve 14 is moved to the position shown in Figs. 4 and 14 closing all ports. To relieve the pressure on piston 73 and allow valve-disk 65 to close the nozzle-valve, the handle of valve 14 is moved to the horizontal position, opening the drain-port and closing the inlet-port 15^a (Fig. 14). As the water starts to discharge from cylinder 67, spring 75 moves the piston downward, and as the valve-disk enters the path of the stream of water passing through waterway 60, the pressure on the back of the valve-disk drives and holds it to its seat.

It will be observed that while the movements following the operation of control-valves 14 and 25 are entirely independent of each other, they may be operated simultaneously, and at the same time the pipe 85 may be rotated by means of lever 29. This enables the operator of the stand-pipe to not only strike a certain point with the stream of water, but also to wet or wash down the entire area within the radius of 90 the water pressure. Thus, for instance, the pipe may be lowered to bring the nozzles to the lowermost position, and then, assuming that any one or more nozzle-valves are open, the pipe may be caused to rise and at the same time slowly rotate with the result that the water would first strike near the pipe at one side of the floor area and then slowly sweep across the floor to the opposite side of the pipe; the pipe is now rotated in the 100 opposite direction causing the stream to sweep back again at a greater distance from the pipe, and so on until the entire area is covered.

I do not claim herein the Y-fitting 10, 105 *per se*, as that fitting forms the subject-matter of divisional application Serial No. 195,732, filed October 10, 1917. Nor do I claim herein the control-fitting 13, *per se*, 110 as that fitting forms the subject-matter of divisional application Serial No. 195,731, filed October 10, 1917. Nor do I claim herein the nozzle-valve 9, *per se*, as that valve forms the subject-matter of divisional application Serial No. 195,733 filed October 115 10, 1917.

What I claim is:

1. In a stand-pipe system for buildings, the combination of a movable stand-pipe, means for moving same, hydraulically operated nozzle-valves mounted on fittings in said pipe, control-pipes and hand operated valves for controlling said nozzle-valves, said control-pipes being carried within the stand-pipe, and means for securing said control-pipes against lateral displacement, substantially as set forth.

2. In a stand-pipe system for buildings, the combination of a movable stand-pipe, means for moving same, hydraulically oper-

ated nozzle-valves mounted on fittings in said pipe, control-pipes and hand operated valves for controlling said nozzle-valves, said control-pipes being carried within the 5 stand-pipe, and means for securing said control-pipes against lateral displacement while allowing lengthwise expansion or contraction, substantially as set forth.

3. In a stand-pipe system for buildings, 10 the combination of a movable stand-pipe, means for moving same, hydraulically operated nozzle-valves mounted on fittings in said pipe, a control-fitting in said pipe having hand operated valves mounted thereon for 15 controlling said nozzle-valves, control-pipes connecting said hand operated valves with said hydraulically operated valves, each control-pipe extending from a hand-valve through the wall of said control-fitting and 20 inside of the stand-pipe to a nozzle-valve fitting and through said fitting to the nozzle-valve, and means for securing said control-pipes against lateral displacement within the stand-pipe, substantially as set forth.

25 4. In a stand-pipe system for buildings, the combination of a movable stand-pipe, means for moving same, hydraulically operated nozzle-valves mounted on fittings in said pipe, control-pipes and hand operated 30 valves for controlling said nozzle-valves, said control-pipes being carried within the stand-pipe and arranged in sections, expansion-joints for coupling the sections, and means for securing said pipes against lateral 35 displacement, substantially as set forth.

5. In a stand-pipe system for buildings, the combination of a movable stand-pipe, means for moving same, hydraulically operated nozzle-valves mounted on fittings in 40 said pipe, control-pipes and hand operated valves for controlling said nozzle-valves, said control-pipes being carried within the stand-pipe and arranged in sections, expansion-joints for coupling the sections, and 45 perforated retaining plates for holding said joints in position and securing said pipes against lateral displacement, substantially as set forth.

6. In a stand-pipe system for buildings, 50 the combination of a movable stand-pipe, means for moving same, fittings in said pipe having branches upon which hydraulically operated nozzle-valves are mounted, control-pipes and hand operated valves for 55 controlling said nozzle-valves, said control-pipes being carried within the stand-pipe and arranged in sections, expansion-joints for coupling the sections, and means for securing said pipes against lateral displacement, said means and said expansion-joints being located within said fittings, substantially as set forth.

7. In a stand-pipe system for buildings, the combination of a movable stand-pipe,

means for moving same, fittings in said 65 pipe having branches upon which hydraulically operated nozzle-valves are mounted, control-pipes and hand operated valves for controlling said nozzle-valves, said control-pipes being carried within the stand-pipe 70 and arranged in sections, expansion-joints for coupling the sections, and means for securing said joints in position and whereby said pipes are secured against lateral displacement, said means and said expansion-joints being located within said fittings, substantially as set forth.

8. In a stand-pipe system for buildings, the combination of a movable stand-pipe, means for moving same, fittings in said 80 pipe having branches upon which hydraulically operated nozzle-valves are mounted, control-pipes and hand operated valves for controlling said nozzle-valves, said control-pipes being carried within the stand-pipe 85 and arranged in sections, expansion-joints for coupling the sections, two perforated retaining plates between which said joints are held and whereby said pipes are secured against lateral displacement, said 90 joints and retaining plates being located within said fittings, and means securing said plates, substantially as set forth.

9. In a stand-pipe system for buildings, the combination of a movable stand-pipe, 95 means for moving same, fittings in said pipe having branches upon which hydraulically operated nozzle-valves are mounted, the bodies of said fittings being U-shaped 100 in cross-section and provided with covering plates, control-pipes and hand operated valves for controlling said nozzle-valves, said control-pipes being carried within the stand-pipe and arranged in sections, expansion-joints for coupling the sections, two 105 perforated retaining plates between which said joints are held and whereby said pipes are secured against lateral displacement, and two sets of lugs within said fitting and between which said plates and joints are locked, substantially as set forth.

10. In a stand-pipe system for buildings, the combination of a movable stand-pipe, means for moving same, fittings in said 115 pipe having branches upon which hydraulically operated nozzle-valves are mounted, the bodies of said fittings being U-shaped in cross-section and provided with covering plates, hand operated valves and hose connections carried by said plates, control-pipes and hand operated valves for controlling said nozzle-valves, said control-pipes being carried within the stand-pipe and arranged in sections, expansion-joints for coupling the sections, two perforated retaining plates 120 between which said joints are held and whereby said pipes are secured against lateral displacement, and two sets of lugs with-

in said fittings and between which said plates and joints are locked, substantially as set forth.

11. In a stand-pipe system for buildings, the combination of a rotary and vertically movable stand-pipe, nozzle-valves and nozzles carried by said pipe, means for rotating said pipe, means for moving said pipe vertically, means for controlling said valves, all said means being operated or controlled from an operating station, two or more water supply connections for said pipe, a telescoping connection at the base of said pipe and through which the water is supplied to the stand-pipe, and check-valves in said supply connections, substantially as set forth.

12. In a stand-pipe system for buildings, the combination of a rotary and vertically movable stand-pipe, a hydraulic-lift for moving said pipe vertically, means for rotating the pipe, one or more nozzle-valves and nozzles carried by said pipe, means for controlling said valve or valves from a distant point, and a water supply connection for supplying water to the stand-pipe through the hydraulic-lift, substantially as set forth.

13. In a stand-pipe system for buildings, the combination of a rotary and vertically movable stand-pipe, a hydraulic-lift for moving said pipe vertically, means for rotating the pipe, one or more nozzle-valves and nozzles carried by said pipe, means for controlling said valve or valves from a distant point, telescoping pipe sections within said lift, and a water supply connection for supplying water to the stand-pipe through said telescoping connection, substantially as set forth.

14. In a stand-pipe system for buildings, the combination of a rotary and vertically movable stand-pipe, a hydraulic-lift for moving said pipe vertically, means for rotating the pipe, one or more hydraulically operated nozzle-valves and nozzles carried by said pipe, hand-valves located at an operating station and pipe connections from said valves to said lift and nozzle-valves for controlling the same, telescoping pipe sections within said lift, and a water supply connection for supplying water to the stand-pipe through said telescoping connection, substantially as set forth.

15. In a fire extinguishing system, the combination of a water supply pipe, outlets at several points in said pipe, hydraulically operated valves for controlling said outlets, control-pipes for said valves carried within said pipe, means for securing said control-pipes against lateral displacement, a fitting in said pipe through which said control-pipes project, valves for said control-pipes, and supply connections for said valves, substantially as set forth.

16. In a fire extinguishing system, the combination of a water supply pipe, outlets at several points in said pipe, hydraulically operated valves for controlling said outlets, control-pipes for said valves carried within said pipe, means for securing said control-pipes against lateral displacement, a fitting in said pipe having a series of stuffing-boxes through which said control-pipes project, valves for said control-pipes, and supply connections for said valves, substantially as set forth.

17. In a fire extinguishing system, the combination of a water supply pipe, outlets at several points in said pipe, hydraulically operated valves for controlling said outlets, control-pipes for said valves carried within said pipe, means for securing said control-pipes against lateral displacement, a fitting in said pipe having a series of stuffing-boxes through which said control-pipes project, valves for said control-pipes, supply connections for said last named valves, and a second series of stuffing-boxes through which said supply connections reenter said fitting, substantially as set forth.

18. In a fire extinguishing system, the combination of a water supply pipe, outlets at several points in said pipe, hydraulically operated valves for controlling said outlets, control-pipes for said valves carried within said pipe and arranged in sections, expansion-joints for coupling the sections, means for securing said control-pipes against lateral displacement, a fitting in said pipe through which said control-pipes project, valves for said control-pipes, and supply connections for said valves, substantially as set forth.

19. In a fire extinguishing system, the combination of a water supply pipe, outlets at several points in said pipe, hydraulically operated valves for controlling said outlets, control-pipes for said valves carried within said pipe and arranged in sections, expansion-joints for coupling the sections, means for securing said control-pipes against lateral displacement, a fitting in said pipe having a series of stuffing-boxes through which said control-pipes project, valves for said control-pipes, supply connections for said last-named valves, and a second series of stuffing-boxes through which said supply connections reenter said fitting, substantially as set forth.

20. In a fire extinguishing system, the combination with a water supply pipe having outlets at several points in said pipe, of hydraulically operated valves for controlling said outlets, said valves each having a straight waterway, a valve seat set at an angle in said waterway, a valve chamber projecting from the waterway at a corresponding angle, a piston chamber above the valve chamber having a piston attached to

the valve stem, and a water inlet to said piston chamber below the piston, substantially as set forth.

21. In a fire extinguishing system, the combination with a water supply pipe having outlets at several points in said pipe, of hydraulically operated valves for controlling said outlets, said valves each having a straight waterway, a valve seat set at an angle in said waterway, a valve chamber projecting from the waterway at a corresponding angle, a piston chamber above the valve chamber having a piston attached to the valve stem, a water inlet to said piston chamber below the piston, control-pipes connected to said inlets and extending to an operating station, and hand operated valves through which said control-pipes are connected to the water supply and whereby said hydraulically operated valves are controlled, substantially as set forth.

22. In a stand-pipe system for buildings, the combination with a movable stand-pipe and means for moving same, of fittings in said pipe at several points, hydraulically operated valves mounted on said fittings, nozzles mounted on said valves, said valves each having a straight waterway, a valve seat set at an angle in said waterway, a valve chamber projecting from the waterway at a corresponding angle, a piston chamber above the valve chamber having a piston attached to the valve stem, a water inlet to said piston chamber below the piston, control-pipes connected to said inlets and extending to an operating station, and hand operated valves through which said control-pipes are connected to the water supply and whereby said hydraulically operated valves are controlled, substantially as set forth.

23. In a stand-pipe system for buildings, the combination of a stand-pipe having Y-fittings therein at several points, and Y-valves mounted on said fittings, said valves having a straight waterway, a valve seat set in a recess in said waterway and of larger

diameter than the waterway, a valve chamber set at an angle to said waterway and perpendicular to said seat and of a depth to permit withdrawal of the valve entirely from the waterway, substantially as set forth.

24. In a stand-pipe system for buildings, the combination with a movable stand-pipe and means for moving same, of Y-fittings in said pipe at several points, and Y-valves mounted on said fittings, said valves having a straight waterway, a valve seat set in a recess in said waterway and of larger diameter than the waterway, a valve chamber set at an angle to said waterway and perpendicular to said seat and of a depth to permit withdrawal of the valve entirely from the waterway, substantially as set forth.

25. In a stand-pipe system for buildings, the combination with a movable stand-pipe and means for moving same, of Y-fittings in said pipe at several points, hydraulically operated Y-valves mounted on said fittings, said valves having a straight waterway, a valve seat set in a recess in said waterway and of larger diameter than the waterway, a valve chamber set at an angle to said waterway and perpendicular to said seat and of a depth to permit withdrawal of the valve entirely from the waterway, a piston chamber above the valve chamber having a piston attached to the valve stem, a water inlet to said piston chamber below the piston, control-pipes connected to said inlets and extending to an operating station, and hand operated valves through which said control-pipes are connected to the water supply and whereby said hydraulically operated valves are controlled, substantially as set forth.

This specification signed and witnessed this 22nd day of March, 1917.

WILLIAM F. CONRAN.
